HEAT EXCHANGING APPARATUS

Charles Adolphe Hubert, Strasbourg, France

Application December 5, 1934, Serial No. 756,023
In France July 4, 1934

4 Claims. (CL 257—248)

This invention relates to improvements in heat exchanging apparatus.

With the known heat exchange apparatus embodying finned tubes, especially for waste gas economizers, soot deposits are produced as a result of the continuously altering section of the smoke passages and particularly between the tubes of the vertical rows of tubes, that is at the points of largest section where there is necessarily a reduction in the speed of the gas and which cannot be reached on cleaning the smoke passages by the usual cleaning media (jet stream, cleaning brushes, chains or the like).

Also, the successive alterations in the section of the smoke passages deleteriously influence the regularity in the flow of the heating medium. The efficiency of the heat exchange apparatus is thereby greatly reduced.

It has already been proposed in heat exchange apparatus formed of finned tubes to avoid the above-mentioned defects by providing passages of which the section either does not alter greatly or does not alter at all. In such apparatus, the fins are not fitted to the body of the tube itself but to two walls located preferably tangentially to the body of the tube and which fins are connected together by suitable struts.

In the known apparatus of this kind, the walls as well as the fins are straight and extend vertically from top to bottom of the apparatus, so that the flow of heating medium can pass between them easily and swiftly without being subjected to frequent changements of speed.

According to the invention the efficiency of the heat exchange in heat exchange apparatus of this kind will still be increased, by arranging the tube fins or walls or both simultaneously in such a way as to impart to the heating medium a certain swirling effect causing said medium to sweep intimately the walls of the passages. In order to obtain this result the tube fins or walls or both simultaneously are shaped and directed so as to form passages in broken or wave-like lines.

The drawings show embodiments of the heat exchange apparatus according to the invention.

Fig. 1 is an elevation view of an ordinary finned tube with parallel straight walls tangential to the tube and straight fins projecting perpendicularly from said walls.

Fig. 2, 3 and 4 are cross sections of heat exchanging apparatus formed by placing side by side vertical rows of such tubes.

Fig. 5 is a corresponding plan view.

Fig. 6 is a cross section of heat exchanging apparatus with sloping tube walls.

Figs. 7 and 8 are cross sections of heat exchanging apparatus with curved tube walls.

Figs. 9, 10 and 11 are fragmental elevation views of heat exchanging apparatus with wave and broken line and sloping fins.

In the various drawings 1 always indicates the body of the finned tube; 2 the two walls extending tangentially to the body of the tube; 3 the fins arranged on the walls; 4 the transverse struts extending between the two walls and 5 the 10 passages formed by the fins and walls.

Figs. 1 and 2 show the known basic form of the finned tube serving for the formation of the heat exchange device. The two straight walls 2 extend parallel to the axis of the tube body 1 and 15 the fins 3 extend perpendicularly from the walls and are also straight so that when several rows of superposed finned tubes are placed side by side and used for the purpose of forming a heat exchange apparatus, continuous straight vertical channels 5 of constant section are formed. The end flanges 7 of the finned tubes may have exactly the same dimensions as the outer periphery of the pairs of fins on the body of the tube so that the fins of all the tubes come into contact 25 both laterally and in the vertical direction (Fig. 2) or they can be somewhat wider (Fig. 3) or wider and higher (Fig. 4). In the two latter cases the passages formed between the fins are in communication with one another.

Now according to the invention the passages 5 instead of being straight, are arranged to produce a certain swirling effect in the gas by a corresponding formation of the walls 2 or of the fins 3 or of both simultaneously.

This result is obtained:

In Fig. 6, simply by sloping the walls 2 in the opposite direction from one horizontal row of tubes to the next whereby zig-zag channels are formed.

In Fig. 7 by curving the walls 2 so that the passages 5 are formed by a successive series of circular segments.

In Fig. 8 by a curved formation of the walls 2 and at the same time with the tubes 1 staggered in the horizontal tube rows so that wave-like channels 5 are formed.

In Figs. 9, 10 and 11, which show partial longitudinal sections of heat exchange devices, by the special formation or arrangement of the fins 3, preferably on the vertical walls 2 so that they either extend in wave or zig-zag lines or are simply sloped in opposite directions from row to row.

I claim:

1. A heat exchanging apparatus comprising several adjacent rows of superposed finned tubes wherein the fins project perpendicularly from two parallel walls tangential to the tubes, said fins and tangential walls being so formed and disposed that the passages therebetween have a progressively varying direction.
- 5 2. A heat exchanging apparatus comprising several adjacent rows of superposed finned tubes wherein the fins project perpendicularly from two parallel walls tangential to the tubes, said walls changing progressively in direction and the fins thereon being straight.
- 10 3. A heat exchanging apparatus comprising several adjacent rows of superposed finned tubes wherein the fins project perpendicularly from two parallel walls tangential to the tubes, said walls being straight and the fins thereon changing progressively in direction. 5
4. A heat exchanging apparatus comprising several adjacent rows of superposed finned tubes wherein the fins project perpendicularly from two parallel walls tangential to the tubes, said walls and fins changing progressively in direction. 10

CHARLES ADOLPHE HUBERT.
